DESIGN FOR A COAT

Molly Levy, New York, N. Y.

Application December 5, 1940, Serial No. 97,079

Term of patent 3½ years

To all whom it may concern:

Be it known that I, Molly Levy, a citizen of the United States of America, residing in New York city, county of New York and State of New York, have invented a new, original, and ornamental Design for a Coat, of which the following is a specification, reference being had to the accompanying drawing, forming part thereof, wherein,

Figure 1 is a front view of a coat showing my new design.

Figure 2 is a rear view of the coat shown in Figure 1.

The characteristic feature of my design resides in the combination on the coat disclosed of the seamless sleeve and yoke section in the front in association with the set in sleeve and yoke section in the rear, as shown.

I claim:

The ornamental design for a coat, substantially as shown and described.

MOLLY LEVY.
